UNITED STATES PATENT OFFICE.

EUGENE C. RICHARD, OF FLINT, MICHIGAN, ASSIGNOR TO GENERAL MOTORS CORPORATION, OF DETROIT, MICHIGAN, A CORPORATION OF DELAWARE.

VACUUM PUMP SYSTEM.

Application filed April 15, 1920. Serial No. 374,177.

To all whom it may concern:

Be it known that I, EUGENE C. RICHARD, a citizen of the United States, and a resident of Flint, county of Genesee, and State of Michigan, have invented certain new and useful Improvements in Vacuum Pump Systems, of which the following is a full, clear, concise, and exact description, such as will enable others skilled in the art to which the invention relates to make and use the same, reference being made therein to the accompanying drawings, which form a part of this specification.

This invention relates to internal combustion engine fuel feeding systems of the vacuum type wherein liquid fuel is supplied to the engine from a main reservoir located at a lower level.

It is well known that under certain conditions, the suction in devices as heretofore employed is not sufficient to create the proper vacuum effect in the vacuum tank to elevate the fuel from the reservoir. It is one of the objects of this invention to overcome this difficulty by providing a device that will insure suction enough under all conditions to create a sufficient vacuum in the tank to cause the transfer of fuel from the reservoir to the tank in sufficient quantities to supply the carburetor.

Another object of the invention is the provision of a suction transformer, intensifier or booster for the main suction device that is controlled by means associated with the operation of the engine in such a manner that it is caused to operate only under certain engine conditions.

Another object of the invention resides in the construction, arrangements, and operation of the valves and valve operating mechanisms in the different parts of the structure and in certain other details of construction.

Other objects and advantages of the invention will appear from the following description and claims:

In the drawings:

Fig. 1 is a side elevation of the device as applied to a motor vehicle.

Fig. 2 is a vertical section of the intake and venturi device, parts broken away.

Fig. 3 is an end elevation of the venturi forming member with the cap removed.

Fig. 4 is a vertical section of the vacuum tank, parts broken away.

Fig. 5 is a vertical section of the upper portion of the tank showing the double valve and valve operating mechanism.

Fig. 6 is a horizontal section of the tank in the line 6—6, looking in the direction of the arrows.

Fig. 7 is a detail sectional view showing a modified form of dump valve.

Fig. 8 is a side elevation of another and in some respects, a preferred form of the device as applied to the engine.

Fig. 9 is a vertical section of the same, parts being broken away.

Fig. 10 is a vertical section of another modified form of the device.

Fig. 11 is a side elevation of still another modified form of the device.

Referring to the drawings, the number 1 designates the intake manifold, 2 the carburetor, 3 the throttle valve, and 4 a receptacle or vacuum tank of an internal combustion engine. The receptacle or tank 4 may be separate from, or connected to, the carburetor, but for the purpose of illustration it is shown as being separate from the carburetor and spaced therefrom.

The vacuum tank 4 which may be of any shape or material and formed in any convenient manner is preferably composed of two chambers: viz, the vacuum chamber 9 which may be termed the intermediate chamber and the lower chamber 10 separated from the vacuum chamber 9 by a diaphragm or partition 11 and which supplies the carburetor with fuel received from the intermediate vacuum chamber.

An upper or overflow chamber 6 may be provided, but in localities where the overflow of the tank is unlikely this chamber may be dispensed with. As shown, the cap 5 is provided with this overflow chamber, although it may be formed in any other convenient manner.

The cap 7 forms a closure for the upper or overflow chamber 6 and has an air passage 8 communicating with a pipe 13 attached to the portion 12 of the cap. The other end of the pipe 13 leads to the carburetor 2, as disclosed in my copending application Serial Number 331,465 filed Oct. 17, 1919.

Mounted within the overflow chamber 6 is the vertically movable float 14 which may be of any form and mounted in any convenient manner. This float carries the valve 16 for closing the passage 8 when the fuel rises in

said overflow chamber beyond a predetermined point. The valve may be mounted in any convenient manner, but as shown, it is fixed relatively to the float. As shown, the

5 float has guiding spindles 15 and 17 which engage in the passage 8, and in a recess in the float guide rod 18, respectively.

The cover which may be made from a single piece of metal is provided with the fuel 19 inlet 19 and with the passage 20 for exhausting the air from the vacuum chamber. The inlet 19 is provided with the downwardly and laterally extending lip 21 for directing the fuel to one side of the lower 15 float, and has attached to it, the fuel conveying conduit 22 which extends to the main fuel reservoir, not shown.

The cover 5 has a depending portion 23 extending into the intermediate chamber and spaced from the walls thereof. This depending portion is provided with a passage 24 which at one end is in communication with the overflow chamber 6; and at its other end with a passage 25, which in 25 turn is in communication with the air vent or passage 26 communicating with the intermediate chamber. The passage 26 may be formed in the screw plug 27, or in any other convenient manner. Access is had to 30 the plug 27 through the aperture 84 which may be closed by the screw plug 85.

A passage or exhaust vent 36 preferably in alignment with the passage 26 affords communication between the exhaust passage 20 and the intermediate chamber.

Slidably mounted in the laterally extending portions 28 of the depending portion 23, are the connected valves 37 which may be termed a double valve and which are adapted 40 to alternately close the passages 26 and 36.

The valves 37 are operated by two lever arms pivoted to the depending portion 23, by means of the pin 29. The arms of this lever are preferably made from sheet metal 45 cut and bent to proper form. The shorter arm 30 (see Fig. 6) is composed of the body portion 33, the laterally extending arms 31, and the parallel perforated ears 32 twisted at right angles thereto, and engaging the pin.

50 The lever arm 30 has a connection with the valves 37 to operate the same. As shown, the body portion of the lever arm 30 has a notch 34 that engages a reduced portion 35 between the valves 37.

The longer lever arm 43 has a body portion 38 having forwardly extending parallel apertured ears 39 twisted at right angles to the body portion 38 and engaging the pivot pin 29. The said body portion 38 has furcations 40 extending rearwardly and laterally. A spring 41 connects each end of the laterally extending arms 31 with the outer end of the corresponding furcation 40. Shoulders 41' on the depending portion,

limit the movements of the longer lever arm 43, the arrangement being such that the springs may pass dead center in either direction.

A float 42 in the intermediate and vacuum chamber has a connection to operate the longer lever arm 43 of the operating mechanism for the valves 37. This connection may be of any appropriate form. As shown, the float is mounted on a sleeve 44 slidably mounted on the guide rod 18. The sleeve, is shown, extends above the float and is provided with shoulders 45, 45 engaging above and below the furcations 40 of the longer lever arm 43.

80 A fitting 46 is secured to the partition 11 and has a depending portion 47 with a passage 48 therethrough connecting the intermediate and lower chambers. The lower end of the passage 48 is closed by the dump valve 49 secured to the depending portion 47 by one or more screws 50, in such a manner as to permit a limited pivotal movement of the valve 49.

The valve 49 is positively operated in one 90 direction by mechanism operated by the float and in the other direction by the counter-weight 51. The valve is located normally below the level of the liquid fuel in the lower chamber in order to seal the valve 95 connection.

Any appropriate means may be employed for positively operating the valve by the float 42. That shown, consists of a rod 52 mounted in a sleeve 53 in order to reduce 100 friction. The sleeve is secured to the fitting 46 and extends upwardly through a groove provided in the float 42. The rod 52 extends slightly above the sleeve 53 and is engaged by the integral extension 54 of the 105 longer lever arm 43. The arrangement of the rod 52 and extension 54 is such that the extension does not engage the rod until at the moment the valve 37 closes the passage 36.

110 In the modified form, shown in Fig. 7, the dump valve 49' is closed by a light spring 55 mounted on the pivot screw 56. One or more pivot screws with their springs may be employed.

115 Assuming that the intermediate chamber is empty, the valves 37 will be in the position shown in Fig. 5 and the valve 49 will be closed. The air in the chamber 9 will be exhausted through the passages 36 and 20 thus causing the fuel to enter from the main reservoir through the passage 19. The fuel rising in the chamber 9 causes the float 42 to rise thus raising the lever arm 43. When the lever arm 43 has been raised sufficiently to cause the springs 41 to pass the fulcrum pin 29, the levers 30 and 43 will be caused to quickly operate the valves 37 to open the passage 26 and close the passage 36 and simultaneously open the dump valve 49.

The closing of the passage 36 cuts off the suction and the opening of the passage 26 permits air to enter the chamber 9 through the pipe 13 passage 8, chamber 6 and passages 24, 25 and 26 into the chamber 9 restoring it to atmospheric pressure. The opening of the dump valve permits the fuel to pass through to the lower chamber and into the carburetor through the passage 57 and pipe 58.

An air duct 86 arranged externally of the tank, connecting the chambers 6 and 10, as shown in dotted lines in Fig. 4, establishes communication between them, to thus permit air to pass from one chamber to the other.

Should the vehicle be in a position in which the main reservoir is above the vacuum tank while the valves are in the position shown in Fig. 4, the fuel will continue to enter through the passage 19, filling the same; and running through the passages 26, 25 and 24 into the overflow chamber, will cause the float 14 therein to rise and close the passage 15, thereby preventing the fuel from overflowing into the carburetor.

A main suction or exhaust pipe 59 is attached to the exhaust passage 20 and is connected to the intake manifold beyond the throttle valve 3. As illustrated in Fig. 2, this connection is made by means of a venturi device 60.

A suction intensifier or venturi device 60 is employed to assist in lowering the pressure in the vacuum tank 4, and it is immaterial how this device is associated with the main suction arrangement. In the preferred form, however, the venturi has one end of the passage 61 containing the restriction 62, secured in the intake manifold at 82 and having its opposite end communicating with the atmosphere. A laterally extending passage 63 communicates with the passage 61 through a restricted aperture 64. The tube 59 is connected to the laterally extending passage 63.

The outer end 65 of the venturi device 60 is enlarged and provided with the groove 66 on the face thereof. This groove forms two seats 72 and 73 in the outer end of the venturi, on which is seated the valve 67 having the outwardly extending recessed valve stem 68, slidably mounted in an enlarged portion of a passage through the cap 69 which is screw-threaded to the outer end of venturi device. A light spring 70 presses the valve 67 against the seats 72 and 73 on the outer end of the venturi. One or more apertures 71 in the enlarged outer end 65 affords a passage for air into the recess 66.

To the outer end of the cap 69 is attached one end of the tube 74, the other end of which is secured to some portion of the engine that produces suction that varies inversely as the suction above the throttle. As shown the tube 74 is secured to the intake

at 83 just below the throttle valve 3. A passage 75 from the recess in the valve stem, communicates with the chamber formed by the cap 69.

By the above arrangement, it will be seen that there is a passage leading from the intake above the throttle to the inner side of the valve 67, and a passage leading from the intake just below the throttle valve to the outer side of valve 67.

It is well known that when an engine is running with the throttle nearly closed, the suction above the throttle is considerably greater than that below it, and that the difference decreases as the throttle is opened until the suction on the two sides becomes equalized.

This principle is taken advantage of to automatically operate the valve mechanism described above.

It will be noted that the area of the valve on the seat 72 is much less than that on the seat 73.

The spring 70 tends to hold the valve 67 on the valve seat 72 at all times. Hence, in starting the engine, no air is received into the manifold to interfere with the starting of the engine. This feature I regard as an important one.

While the valve 67 is seated, the air is exhausted from the vacuum tank through what may be termed the main suction device, i. e., through the pipe 59 and passages 63, 64, and 61. In other words, the venturi does not function, as such.

As the throttle is opened, the suction on each side of the valve becomes more and more nearly equalized, until the suction operating on the larger area on the outer side of the valve, overcomes that operating on the relatively small area on the inner side of the valve, causes the valve to become unseated against the tension of the spring, and air entering through the passage 71 and through the venturi boosts or intensifies the suction in the main suction device. In other words, when the sub-atmospheric pressure on each side of the valve 67 becomes nearly equalized the pressure of the air through the apertures 71 unseats the valve against the tension of the spring and the air enters the venturi.

It is to be understood that this suction transformer or venturi device is not limited in its use to the particular form of tank described above, as it may be used equally as well on other forms of vacuum tanks.

The arrangement of the spring and valve mechanism is preferably such that the valve is automatically unseated when the throttle is about three-fourths open, since under ordinary conditions, with the throttle less open, the main suction device is sufficient to supply the vacuum tank with fuel. The arrangement, however, may be varied so that

the valve will become unseated at other positions of the throttle.

By this arrangement it will be noted that the air is introduced into the intake manifold during comparatively open throttle conditions, and the introduction of air into the mixture at this time has been found to aid in its combustion.

In Figs. 8 and 9, I have shown a valve for the venturi as being manually operated. This valve may be operated by any convenient means within reach of the operator of the car. As shown, it is operated by the throttle control. The spring-pressed valve 67' mounted in the cap 69' has its stem slotted as at 75' to receive a cam member 76, having a cam face 77 that engages a roller 78 within the outer portion of the slot. The spring normally tends to hold the valve closed and it is opened by the cam face 77 engaging the roller 78. The cam member 76 is pivotally attached to an extension 79 on the throttle operating arm 80. It will be noted that the cam and valve arrangement is such that the valve remains closed until the throttle is opened to a considerable extent. The arrangement may be varied to suit circumstances and conditions.

In the modification shown in Figure 11, a moving fluid from some source is caused to pass through a venturi which exhausts the air from the vacuum chamber. As shown, the venturi 60' is secured to the exhaust manifold 81. Exhaust gases pass through the venturi into the air, preferably through a muffler, thus exhausting the air from the vacuum chamber 4 through the pipe 59', and causing the fuel to flow through the pipe 22 into the said chamber.

Since the suction or pressure in the intake and exhaust vary inversely, instead of connecting the outer end of the tube 74 to the intake anterior to the throttle, as shown in Fig. 2, it may be connected to the exhaust passage 81 in any manner. As shown in Fig. 10, this is accomplished by attaching the outer end of the tube 74 to the venturi 60' at 83'. The exhaust gases passing through the venturi, preferably through a muffler 82, create a suction in the tube 74 that varies inversely as the suction in the main device. In this form, as in the form shown in Fig. 2, the differential suction in the main and auxiliary devices will operate the valve 67.

While I have described what I deem to be a preferred form of my invention, it will be obvious that various changes and modifications may be made, without departing from the spirit and scope thereof as indicated in the appended claims.

I claim:

1. In combination with the intake passage of an internal combustion engine, a chamber into which fuel for said engine is to be lifted,

means for utilizing the suction in said passage for creating a more intense suction for lifting the fuel to said chamber, said means including a valve having a portion normally exposed to atmospheric pressure, and a spring for closing the same, and means associated with the operation of the engine for opening the valve.

2. In combination with the intake passage of an internal combustion engine, the throttle therefor, and a fuel supplying orifice opening into said manifold, means comprising a venturi device for intensifying suction derived from said manifold as compared to that existing at said orifice and for applying said intensified suction for lifting fuel to be supplied to said orifice, said means also including a valve and means tending to close the same, and means associated with the operation of the engine for controlling the operation of said valve, said last named means operating only when the throttle has opened to a predetermined amount.

3. In a mechanism of the class described including a throttle for an internal combustion engine, the combination of a main suction device, an auxiliary suction device having a passage therethrough, a valve for said passage, a spring for normally closing said valve, and means associated with the operation of the engine for opening said valve only when the throttle has been opened a predetermined amount.

4. In an internal combustion engine fuel feeding system of the vacuum type, a throttle for said engine, a vacuum tank, a conduit for conveying liquid fuel thereto from a lower level reservoir, a suction device including a suction intensifier provided with a normally closed valve, and means controlled by said throttle for opening said valve to intensify the suction, substantially as described.

5. In a mechanism of the class described, including a throttle mechanism for internal combustion engines, the combination of a vacuum tank, suction means associated with the operation of the engine for lowering the pressure in said tank, said means having a normally closed valve associated therewith, said valve being movable by said throttle mechanism permitting the flow of a continuous stream of fluid through said means only when said throttle has been opened a predetermined amount, substantially as described.

6. In an internal combustion engine fuel feeding system of the vacuum type, a vacuum tank, a conduit for conveying liquid fuel thereto from a lower level reservoir, a main suction device for lowering the pressure in said tank, an auxiliary suction device comprising a venturi for assisting in lowering the pressure in said tank, said auxiliary suction device having a passage therethrough, a valve for the said passage, a

- spring normally closing said valve, and closing said dump valve, substantially as described.
- 5 means incident to the operation of the engine for opening said valve to permit said auxiliary suction device to become operative to assist in lowering the suction in said vacuum tank.
7. In a device of the class described, a suction intensifier including a device having a venturi passage therethrough and a valve 10 for closing one end of said passage, and a spring for closing said valve.
8. In an internal combustion engine fuel feeding system of the vacuum type a main suction device for lowering the pressure in 15 the vacuum tank, an auxiliary suction device including a venturi for assisting in lowering the pressure in said tank, a passage through said venturi, a valve spring pressed to close said passage and manually operated 20 means for opening said valve.
9. A venturi suction device having a main member and a member extending laterally therefrom, a passage having a restricted portion through said main member, a passage through said laterally extending member communicating with said restricted portion, and a spring pressed valve closing the outer end of the passage in said main member, and a cam member adapted to be operated by throttle controlling means for lifting said valve from its seat, substantially as 30 described.
10. A vacuum tank for fuel feeding systems, including an upper vacuum chamber, 35 a lower fuel receptacle, a partition between said chamber and receptacle, a cover for said tank, said cover having an air vent, an exhaust vent and a fuel passage therein, a double valve for alternately opening and 40 closing said vents, a float in said chamber, a lever mechanism operated by said float for actuating said valves, a dump valve between said chamber and receptacle and means operated by the valve actuating levers for 45 opening said dump valve simultaneously with the closing of said suction vent and the opening of said air vent, and means for
11. In a vacuum tank having a cover, and a float therein, an air passage and exhaust passage through said cover, a single double-acting valve integrally connected for opening and closing said passages, a dump valve means operated by said float for actuating 55 said double-acting valve and for opening the dump valve, and a weight for closing the dump valve, substantially as described.
12. A cover for vacuum tanks having a fuel passage therethrough, and a fuel deflector at the bottom of said passage; a chamber in the upper portion thereof and a cap for said chamber; a depending portion having suction and air passages therethrough; and means on said depending portion for supporting valves to close said suction and air passages and other means for supporting the valve operating mechanism, substantially as described.
13. In a fuel feeding system for internal 70 combustion engines, a receptacle for supplying fuel to the engine, a lower level reservoir, means for transferring said fuel from said reservoir to said receptacle, said means including a venturi and a valve therefor, 75 and means independent of the suction of the engine connected with the throttle for opening said valve by the operation of said throttle when said throttle has been moved a predetermined distance.
14. In a fuel feeding system for internal combustion engines, a receptacle for supplying fuel to the engine, a lower level reservoir, a throttle for said engine, means for utilizing the suction of said engine for 80 conveying fuel from said reservoir to said receptacle, and manually controlled means for continuously intensifying said suction, said last named means being inoperative during the initial movement of said throttle 90 from closed position.

In testimony whereof I affix my signature.

EUGENE C. RICHARD.
